UNITED STATES PATENT OFFICE.

JOHAN GUSTAF V. LANG, OF NEW YORK, N. Y., ASSIGNOR TO GREENFIELD PAPER BOTTLE COMPANY, OF NEW YORK, N. Y., A CORPORATION OF NEW JERSEY.

MANUFACTURE OF PAPER BOTTLES.

1,230,177.

Specification of Letters Patent. Patented June 19, 1917.

Application filed September 28, 1915. Serial No. 53,039.

To all whom it may concern:

Be it known that I, JOHAN GUSTAF V. LANG, a citizen of the United States, and a resident of the borough of Manhattan, city 5 of New York, county and State of New York, have invented certain new and useful Improvements Relating to the Manufacture of Paper Bottles, of which the following is a specification.

10 The invention relates to machines for giving to a tube of paper or similar material the form of a bottle and particularly to the kind of machines by which the surplus paper, due to the gradual transition from the 15 larger diameter of the body to the smaller diameter of the throat and neck, is taken up in plaits or folds of one kind or another.

One object of the present invention is to insure the breaking of the paper in the 20 proper places and thus bring about approximate uniformity of the plaits or folds. It has been found that the action of forcing the paper down against a form by engaging the tube at equi-distant points around the circumference by loop-forming members suitably spaced to give room for the finished 25 plaits does not in itself bring about the uniformity of the plaits or folds. This is due to the fact that the paper which is in the 30 tube varies in structure and strength so that it does not bend and break in the same way in each space between the loop-forming members. The loops when formed according 35 to natural tendencies vary considerably in shape and when pressed down the resulting plaits are more or less distorted and the paper is crumpled up instead of forming a smooth fold.

To assist in controlling the forming of the 40 loops there is provided on the face of the loop-forming members thin sheet metal plates which extend into the spaces between said loop-forming members leaving only sufficient room between each of the two adjacent 45 cent thin plates for that part of the paper which connects the loop-portions with the rest of the paper that constitutes the throat and neck portion of the bottle. The paper in this loop portion is pressed down over 50 the thin sheet metal plates by means of plait-pressing members and sufficient pressure is

applied to crease the paper into plaits or folds which extend over the thin metal plates.

According to one feature of my invention 55 the thin sheet metal plates may be more or less springy and in fact may be formed of two spring members which can yield as the plates are withdrawn from beneath the paper in the folds.

Another feature of the invention relates to the providing of loop-forming members with flat springs that constitute yieldable means for engaging the paper in the tube as it is being forced around the neck portion 65 of the mold so as to form the throat portion of a bottle body.

Another feature of the invention relates to the providing of plait-pressing members with yieldable means, preferably in the form 70 of flat springs, so that the loops will be engaged for substantially their full length by said yieldable members.

As showing a specific embodiment of the invention reference is made to the drawings 75 forming a part of this specification and in which drawings,

Figure 1 is a vertical view, partially broken away, of a tube which is to be pressed so as to take the form of a bottle body.

Figure 2 is a vertical view, partially broken away, of a bottle body with an inverted bottom member located in place relative to the body of the bottle.

Fig. 3 is a plan view of the bottle body 85 shown in Fig. 2.

Fig. 4 is a vertical sectional view of a machine which may be utilized to press the paper tube so as to take the form of a bottle. This is a view taken as on the line 4—4 of 90 Fig. 5.

Fig. 5 is a partial plan view of the inner mold and the members arranged about it. In Fig. 4 the tube to be pressed is shown in section, while in Fig. 5 a part of this tube is 95 shown in plan partially pressed.

Figs. 6 and 7 are detail views, respectively, of a loop-forming member and a plait-pressing member, such as are used in the machine shown in Fig. 4.

Fig. 8 is a sectional view taken as on the line 8—8 of Figs. 4 and 6.

Fig. 9 is a vertical sectional view of another form of machine which may be utilized to press the paper tube so as to take the form of a bottle. It will be observed that Fig. 4 is a vertical sectional view looking at the machine illustrated therein from the front, whereas the machine shown in Fig. 9 is a view looking at the machine from the side.

Fig. 10 is a partial plan view of the upper 10 portion of the machine which is shown in Fig. 9. In Fig. 9 the tube to be pressed is shown in section whereas in Fig. 10 the tube is shown partially pressed.

Fig. 11 is a plan view of a machine similar 15 to that shown in Fig. 9 but in the machine shown in Fig. 11 the plait-pressing jaws have a construction similar to that shown in Fig. 15.

Fig. 12 is a detail view of the upper end 20 of a loop-forming member which is like the loop-forming member that is utilized in the machine shown in Figs. 9 and 10.

Fig. 13 is a plan view of the loop-forming member shown in Fig. 12.

Fig. 14 is a detail view of the spring-plate 25 members which are used in the loop-forming members shown in Figs. 12 and 13.

Fig. 15 is a plan view of a loop-forming member such as is utilized in the machine 30 shown in Fig. 11.

The paper tube may be considered to comprise two main members, namely, a bottle body A and a bottom B. This body A is formed by pressing a tube C which is preferably a hollow cylinder so that the surplus paper, due to the gradual transition from the larger diameter of the tube to the smaller diameter of the neck or throat, is taken up into plaits or folds of one kind or another 35 and as has been previously indicated an object of the present invention is to provide a machine which will do this in a practical and commercial manner.

One form of the machine which will accomplish this is shown in Figs. 4 and 5, while another machine differing somewhat in detail is shown in Figs. 9 and 10. A machine having a still further difference in its detail of construction is illustrated in 50 Fig. 11.

The machine shown in Fig. 4 is partially shown in plan in Fig. 5 and the machine shown in Fig. 9 is partially shown in plan in Fig. 10. Each of these machines comprises a frame 1 upon which there is pivotally mounted a series of loop-forming members and a series of plait-pressing members. The loop-forming members of the machine shown in Figs. 4 and 5 are designated by 55 the reference character 2 and the plait-pressing members in the same machine are designated by the reference character 3. In the machine shown in Figs. 9 and 10 the loop-forming members are designated by 2' and 60 the plait-pressing members by 3', while in

the machine shown in Fig. 11 the loop-forming members are designated by the reference character 2'' and the plait-pressing members by 3''. These loop-forming members and plait-pressing members are pivotally mounted at their lower ends upon the frame so that the upper ends of these members are free to be forced inward toward an inner mold 4. This inner mold 4 is secured to or mounted upon the frame 1, said mold having the shape or configuration of a bottle and arranged with the neck or throat portion of the mold uppermost. This mold may be considered to have a body part a, a throat part b and a neck part c. It will be observed, however, that the throat and neck parts merge into each other and for many purposes the throat may be considered not only to include that portion which is technically known as the throat but to include also that portion which is technically known as the neck. It is to be understood, however, that the word throat is to be given a broad construction as an important feature of the present invention relates to the 90 pressing of a tube in such a manner that the superfluous paper which results from the gradual reduction of diameter is formed into plaits or folds. The plait-pressing and loop-forming members coöperate with this 95 mold 4 and they are operated so that the loop-forming members are the ones first forced toward the mold and they are followed, so to speak, by the plait-pressing members which lag behind the loop-forming members. These two sets of members constitute what may be referred to as sets of pivoted arms that coöperate to form in effect a set of duplex members or arms.

Each of the loop-forming members or arms have on their outer sides, to wit, the sides farthest remote from the mold 4, surfaces 5 which are shaped so as to provide cam conformations, and the plait-pressing members or arms also have on their outer sides, to wit, the sides farthest remote from the mold 4, surfaces 6 which are shaped so as to provide cam conformations. These cam-shaped surfaces 5 and 6 are engaged by rollers 7 that are carried upon a ring 8. 105 This ring 8 is operated or forced upwardly through the medium of links 9, arms 10, shaft 11 and handle or arm 12. This ring is guided by depending members 13 which slide in screw-members 14. The shaft 11 is 110 carried by bearings 15 and the construction is such that as the free end of the arm 12 is forced downwardly by the operator the ring 8 will move upwardly in such a manner that the rollers 7 upon the ring will force the 120 loop-forming members and the plait-pressing members toward the mold 4. The cam conformations 5 and 6, however, are constructed so that the plait-pressing members lag behind the loop-forming members. An 125 130

ejector ring 16 may also be provided at the lower end of the mold 4 and this ejector ring can be moved upwardly through the medium of a link 17 which is connected 5 to a lever 18 and it will be manifest that a movement of the ring 16 upwardly will force the formed tube, to wit, the body A, upwardly along the mold so that the formed bottle body can be readily removed from the 10 machine, as by hand.

The tube which is to be pressed in this machine has preferably been waxed, or at least has been made of wax paper, and it is therefore advantageous to heat the forming 15 mold to a slight extent. Where this heating is desired burners 19 or any other suitable heating means may be employed. The mechanism for lifting the ring 8 for ejecting the pressed tube and for heating the 20 mold is shown as being substantially the same in the forms of apparatus shown in Figs. 4 and 9. Each of the loop-forming members of the machine shown in Fig. 4 is provided upon its operating face with a vertically extending spring-member 20 which 25 is secured to the forming-member as by means of a screw 21. These spring-members 20 are preferably in the form of flat springs and about their upper ends there are secured thin curved plates 22 (see particularly Figs. 5, 6 and 8) which extend laterally relative to the forming members. The 30 ends of these plates 22 extend into the spaces between the loop-forming members 2 but they are constructed of such a length that the adjacent ends 22^a 22^a will leave sufficient space for part of the paper to pass, to wit, the part designated by the reference character D. The part D is that part of the paper 35 that connects the paper in the loop with the rest of the paper in the throat or neck. The upper and lower ends of each of the spring-members 20 are free to be pressed toward its forming member as the forming 40 member is forced toward the mold. Each of the plait-pressing members 3 have a flat spring 23 secured to the forming member as by means of a screw 24. Each of the springs 23 extends substantially vertical and 45 the upper and lower ends thereof are free so that they can be forced toward the plait-pressing member 3 as the latter is forced toward the mold 4.

It will therefore be observed that the 50 springs 20 and 23 can adapt themselves to the paper tube C as it is being transformed into a bottle body and that these springs also can adapt themselves to the bottle body when it is in final form.

In performing the invention the loop-forming members are first forced inwardly 55 toward the mold the full distance and they are followed in their operation by the plait-pressing members which force the loops 60 down so as to form plaits or folds which ex-

tend over and which engage the ends 22^a of the curved plate 22. As the upper end of the spring 20 carries the plate 22 it will be observed that these thin plates 22 can yield relatively to the forming members as 70 the latter are forced toward the mold.

The machine shown in Figs. 9 and 10 is similar in its mode of operation to that shown in Fig. 4, but the construction of the parts of the loop-forming members and 75 plait-pressing members differs somewhat in detail.

In the machine shown in Fig. 9 there is a depending spring 25 which is suitably secured to the forming-member 2' in a manner so that the lower end of the spring 25 is free to be forced toward the forming member as the latter is forced toward the mold. On the upper end of each of the forming members 2' there is provided a sheet plate 80 means 26, the latter of which comprises hinged wings 27 and 28 the ends 27^a and 28^a of which are continuously forced toward each other by means of a spring 29. Each of the plait-pressing members is provided 85 with a flat spring 30 the lower end of which can be forced toward the plait-pressing member carrying it as the plait-pressing member is forced toward the mold 4.

In Fig. 11 each of the loop-forming arms 90 is shown as being provided with another form of thin plate that extends into the space between the loop-forming arms. This thin plate just referred to is designated by the reference character 31 and is shown more 100 fully in Fig. 15. This thin plate 31 may be screwed, as by means of a screw 32, directly to the upper free end of the loop-forming arm 2" and the thin plate 31 may be made of a spring-steel if desired; its function and 105 mode of operation, however, are similar in many respects to the thin plate means 22 described in connection with Fig. 4 and to the thin plate means described in connection with the form of press shown in Fig. 9. 110

From what has preceded it will be manifest that the machines shown in Figs. 4, 9 and 11 while differing somewhat in detail are similar in their function and mode of operation.

The improvements herein set forth are not limited to the precise construction and arrangement shown and described, as they may be embodied in various forms and modifications without departing from the spirit and scope of the invention.

What I claim is:

1. A machine for making paper bottles comprising in combination a mold having the shape or configuration of a bottle, loop-forming members arranged about the mold, and means for forcing said forming-members toward the mold, said forming members having at the free ends thereof thin sheet metal plates which extend laterally on 125

each side of the forming members and which sheet metal plates can yield relatively to the forming members.

2. A machine for making paper bottles comprising in combination a mold having the shape or configuration of a bottle and arranged with the neck portion of the bottle uppermost, a series of loop-forming arms arranged about said mold and provided opposite the neck portion of said mold with sheet metal plates which can spring or yield relatively to said forming arms, said sheet metal plates being arranged so as to extend into the spaces between said loop-forming means to leave just sufficient room between each two adjacent plates for the paper which connects the loop portion to the rest of the paper that constitutes the neck of the bottle.
3. A machine for making paper bottles comprising in combination a mold having the shape or configuration of a bottle and arranged with the throat portion of the mold uppermost, a series of loop-forming members arranged about the mold, and means for forcing the loop-forming members toward the mold, said loop-forming members having upon the portion opposite the throat portion of the mold thin sheet metal plates which extend into the spaces between said loop-forming members, said thin sheet metal plates being mounted on said forming members so that the outer ends of the thin metal plates can approach each other, and spring means tending to force said metal plates into extended position.

4. A press for making paper bottles comprising in combination an inner mold having the shape or configuration of a bottle, a series of loop-forming arms surrounding said mold, sheet metal plates secured to said arms and extending into the spaces between them, and yieldable members secured to said arms the lower ends of which yieldable members are adapted to move relatively toward said arms as the arms are forced toward the mold.

5. A machine for making paper bottles comprising in combination a frame, a mold having the shape or configuration of a bottle and mounted upon said frame with the neck or throat portion of the mold extending upwardly, a series of forming members having their lower ends pivotally mounted on said frame, each of said forming members having at its upper free end a sheet metal plate which extends into the spaces on the opposite sides of the forming member carrying said sheet metal plate, each of said forming members also having a yieldable member the upper portion of which is secured to its forming member and the lower portion of which can be forced toward the forming member as the latter approaches the mold.

6. A machine for making bottles comprising in combination a frame, a mold having the configuration of a bottle mounted upon said frame with the neck or throat portion at the top, a series of forming arms arranged about said mold the lower ends of which are pivotally connected to said frame, and means for forcing said arms toward said mold, said forming arms having at their upper free ends sheet metal plates which extend into the spaces between the arms, there also being provided yieldable members in the form of flat springs the upper ends of which are secured to said arms and the lower ends of which are free to be forced toward the forming arms as the latter are forced toward the mold.

7. A machine for making paper bottles comprising in combination a mold having the shape or configuration of a bottle, loop-forming members arranged about said mold, and plait-pressing members arranged about said mold, which plait-pressing members enter the spaces between the loop-forming members, said plait-pressing members being provided with yieldable members that are arranged so that as the plait-pressing members are forced toward the mold said yieldable members can adapt themselves to the loops which are being pressed.

8. A machine for making paper bottles comprising in combination a mold having the form or configuration of a bottle which mold is arranged with the neck or throat portion uppermost, a series of loop-forming members arranged about said mold, a series of plait-pressing members arranged about said mold and entering the spaces between said loop-forming members, and means for forcing said plait-pressing members to final position after the loop-forming members have been forced to loop-forming position, each of said plait-pressing members having secured thereto a flat spring the upper and lower ends of which are free to be forced toward the pressing members as the latter are forced inwardly.

9. A machine for making paper bottles comprising in combination a frame, a mold having the shape or configuration of a bottle and arranged with the neck and throat portion uppermost, a series of loop-forming members arranged about said mold, and a series of plait-pressing members arranged about said mold and entering the spaces between the loop-forming members, which said loop-forming members and plait-pressing members are pivotally mounted at their lower ends upon said frame, and means for forcing the members which are thus pivotally mounted toward the mold, which said means is constructed so that the plait-pressing members lag behind the loop-forming members, each of the loop-forming members having at its upper end a thin sheet
